Radio Corporation of America, a corporation
of Delaware

Application November 3, 1938, Serial No. 238,538

1 Claim. (Cl. 250—20)

The present invention relates to electrical oscillator systems and in particular to systems embodying frequency modulation of a thermionic vacuum tube oscillator.

One object of the present invention is to provide a frequency modulator in which the mean frequency may be varied over a range of frequencies while maintaining a substantially constant width of frequency modulation excursion.

Another object is to embody such a constant band frequency modulator in a generator of frequency modulated signals useful in various applications.

Still another object is to improve and simplify automatic tuning systems as applied to radio receivers by application of my present constant band-width frequency modulation system to the tuning correction system of such receivers.

In my U. S. Patent Number 2,082,317 issued on June 1, 1937, is shown a method of producing and controlling a frequency modulated signal. A thermionic vacuum tube oscillator is partially tuned by the input capacity of a second tube having a condenser connected between grid and plate and a resistor plate load. The input capacity is varied by varying the gain of the capacity tube and the oscillator is hence frequency modulated. A cathode ray tube is used to indicate the response of a circuit to the frequency modulated signal against the signal causing the frequency modulation which may conveniently be taken from the local power line. It is often desirable to vary the mean frequency of the frequency modulated signal over a range of values. If this is done by varying a condenser across the oscillator inductance, the width of the frequency modulation band will become continuously smaller as the mean frequency is decreased.

The present invention embodies means for producing a substantially constant frequency modulation band width as the mean frequency is varied. This equal band width condition is obtained by varying the capacity between plate and grid of the capacity tube in order to vary the mean frequency and by adjusting the capacity across the oscillator inductance to a suitable value. With no capacity across the oscillator inductance except that produced by the capacity tube, the band width of frequency modulation will increase proportional to the mean frequency. However, an added capacity in shunt with the oscillator inductance tends to decrease the frequency modulation band width and by an amount which increases with the mean frequency. In this way substantially constant frequency modulation band widths may be obtained over mean frequency ranges of the order two or three to one. If the capacity tube load resistor and

the oscillator inductance are changed simultaneously, an all wave signal generator may be produced having substantially constant frequency modulation band widths over an extended frequency range.

The present invention may be more fully understood from the detailed description of the various figures of the drawing.

In the drawings:

Fig. 1 shows a simplified circuit embodying the present invention.

Fig. 2 shows a modified simplified circuit.

Fig. 3 shows a complete circuit diagram of a signal generator embodying the present invention.

Fig. 4 shows an automatic tuning radio receiver circuit embodying one form of the invention.

Fig. 5 shows some curves useful in explaining the operation of the invention.

In Fig. 1 is shown a source of oscillation 1 connected to a frequency determining inductance 2. A condenser 3 is connected across the frequency determining inductance to set the mean frequency value of the oscillations. Capacity producing tube 4 having a cathode 7, grid 6 and plate 5 is connected with its grid to cathode circuit across oscillator inductance 2, thru blocking condenser 8 and cathode bias resistor 10 bypassed by condenser 11. Plate 5 is connected to a variable load resistor 9 and a plate energizing battery 16. Heater energizing means is not shown but will be understood to be any conventional means. A variable condenser 14 is connected between grid 6 and plate 5 and grid 6 receives a signal from source 13 thru grid resistor 12. The effective capacity, added by the capacity producing tube 4, across inductance 2 will be capacity 14 times one plus the gain of tube 4 as determined by resistor 9, voltage 13 and the tube characteristics. The frequency of source 1 may hence be varied by varying voltage 13. If source 13 is a periodic voltage, the capacity supplied by tube 4 and hence the frequency of source 1 will be periodically varied in accordance with this voltage. The magnitude of this periodical frequency variation will depend on the various constants as stated above and may be termed the frequency modulation band width. If condenser 14 only is associated in the frequency determining circuits of tube 4 and source 1, the band width of frequency modulation will increase as the mean frequency is increased by decreasing capacity 14 as shown in curve *a* of Fig. 5. Mathematically, the band width of frequency modulation Δf is equal to the mean frequency F times the capacity tube gain A divided by 2 as follows:

$$\Delta f = FA/2$$

where A is the change in capacity tube gain caused by the variation of the applied voltage 13.

It is often desirable to have the frequency modulation band width Δf constant as the mean frequency is varied. If a condenser 3 is connected in shunt with coil 2, the band width Δf is decreased at the higher mean frequencies as shown in curves *b* and *c* in Fig. 5. This is due to the fact that as capacity 14 is decreased, a smaller and smaller part of the total frequency determining capacity is modulated by the action of tube 4 and voltage 13. Curves *a*, *b* and *c* are for band widths against mean frequency where capacity 14 is varied from 10 micro-microfarads at mean frequency of 1.0 to 500 micro-microfarads at minimum mean frequency. Curve *a* is for capacity 3 equal to zero, curve *b* is for capacity 3 equal to 10 micro-microfarads, and curve *c* is for capacity 3 equal to 50 micro-microfarads. Lines *e* and *f* have been drawn on Fig. 5 indicating a two to one frequency range. It will be noted that within this range the total departure from constancy of band width for curve *a* is 100 per cent, for curve *b* is 64 per cent and for curve *c* is only 21 per cent. Lines *d* and *g* have been drawn covering a three to one frequency range showing that curve *a* departs 200 per cent from constancy, curve *b* departs 105 per cent and curve *c* departs 50 per cent. Since it will generally be desired to use only these indicated portions of the curves, the maximum frequency may be limited to points *f* or *g* by a minimum capacity control condenser 15 in shunt with main condenser 14. It will be understood that a part or all of either or both of condensers may be supplied by stray circuit capacities and the minimum capacity of condenser 14 if these capacities are of the proper magnitudes for the purpose set forth above.

Fig. 2 is similar to Fig. 1 except that the power factor of the input capacity of tube 4 is improved by coupling a load resistor 19 to plate 5 thru transformer 17-18. For fixed frequency applications, this transformer may be tuned to the frequency of source 1 by means of condenser 20. The secondary 18 should have fewer turns than primary 17 so that a larger amplified voltage per ohm of the load resistor 19 is produced than if resistor 19 were directly connected to plate 5. In Fig. 2 the condensers 3 and 15 of Fig. 1 are shown omitted being replaced by the stray capacities 21 and 22 respectively.

Fig. 3 shows a complete circuit diagram of a signal generator embodying one form of the present invention and including a cathode ray tube for observing response characteristics of apparatus subjected to the frequency modulated signal. The capacity tube 4 includes a cathode 7, control grid 6, two further grids 75 and 76 and plate 5. Grids 75 and 76 are connected to plate 5 so that the tube operates as a triode although other connections may be used such as tetrode or pentode circuits. Cathode 7 receives its bias from cathode current flowing in resistor 10 bypassed by condenser 11 connected to ground G. Frequency control condenser 14 is connected between grid 6 and plate 5 in order to provide constant frequency modulation band width as set forth above. Plate load resistor 9 is provided to produce the desired gain for frequency modulation. Resistor 9 may be varied by means of switch 74 in order to adjust the frequency modulation band for different frequency bands of the generator. The oscillation generator comprises

the vacuum tube 24 having cathode 26, control grid 25 and plate 23 coupled to one of the oscillator inductances 2, 2' or 2'' by means of range change switches 31 and 32. Control grid 25 receives bias from grid leak 27 and grid condenser 28. Plate voltage is supplied thru resistor 29 and the oscillator inductances are coupled thru blocking condenser 30. Output from the oscillator is supplied to "Apparatus under test" thru lead 35 from a variable tap on output potentiometer 34 coupled to the oscillator inductance being used to generate oscillations thru coupling condenser 33. Capacity tube 4 controls the oscillator frequency by coupling grid 6 to the oscillator inductances thru blocking condenser 8. Frequency modulation under control of the power line frequency is provided by driving grid 6 from a tap on a potentiometer 58 supplied from winding 60 on the power transformer 61 thru the radio frequency isolating choke 57. The system so far described supplies a substantially constant band width frequency modulated signal by varying condenser 14 with continuous control of mean frequency and operable over a number of frequency bands by simultaneously switching oscillator inductances and capacity tube load resistor by means of switches 31, 32 and 74 to "Apparatus under test."

Power for operating the system is supplied from a suitable power supply such as that shown. Power transformer 61 includes a primary winding 62 connectable to a power line plug 63 thru on-off switch 64; heater winding 65 for supplying rectifier 66; high voltage winding 67; and frequency modulation control voltage winding 60. The power supply also includes filter chokes 68 and 69, filter condensers 70, 71 and 72, and bleeder resistor 73. A cathode ray tube 37 is provided for observing the response of the "Apparatus under test" to the frequency modulated signal against the driving signal of power line frequency. Cathode ray tube 37 includes static deflection plates 38, 39, 40 and 50, cathode 54, control grid 53, focus anode 52, final anode 51 and cathode heating means not shown. Suitable electrode potentials for tube 37 are supplied from points on voltage divider 56 connected across high voltage battery 77 or other suitable high direct current voltage source. A vertical deflection is obtained indicating the response of the "Apparatus under test" to the frequency modulated signal by connecting the apparatus output to vertical deflecting plate 38. A horizontal axis is provided by connecting horizontal deflecting plate 40 to the power line voltage from winding 60 thru resistor 59 and across condenser 55. Condenser 55 and resistor 59 are adjusted to vary the phase of the horizontal deflection providing any desired relation of the horizontal deflection and generator frequency.

An additional application of my present invention is shown in Fig. 4 where my constant band width modulator is applied to automatic tuning in a radio receiver. An automatic tuning system for superheterodyne receivers has been shown by S. W. Seeley in U. S. Patent No. 2,121,103, issued June 21, 1938, in which the intermediate frequency signals traversing the intermediate frequency amplifier are applied to a "discriminator" circuit which is in effect a pair of tuned coupled circuits feeding a double diode detector. The phase of the rectified voltage produced by the "discriminator" changes sign when the intermediate frequency signal mean frequency equals the resonant frequency of the tuned

coupled circuits. A frequency correcting device may be operated from this rectified voltage tuning or correcting the variable oscillator frequency of the superheterodyne so that the intermediate frequency signal is centered on the "discriminator" mean frequency.

My present constant band system has a great advantage when applied to such automatic tuning systems since it will give equal correction throughout the tuning range of the oscillator. The modulating voltage of the frequency modulation system is simply replaced by the rectified output of the "discriminator" and the capacity tube is connected across the inductance of the variable frequency oscillator. Fig. 4 shows a superheterodyne radio receiver comprising a radio frequency amplifier 79 connected to antenna A thru coupling condenser 78 and to ground G, first detector 80, intermediate frequency amplifier 81, second detector 82, audio frequency amplifier 83, speaker 84, variable frequency oscillator 86, and discriminator 85 labeled "control voltage generator." The control voltage generator produces a bias voltage which depends on the mean frequency of the intermediate frequency signals as described above. This bias voltage is applied to grid 99 of the capacity control tube 98 by means of grid resistor 97 and across filter condenser 106 which removes radio frequency voltages from the lead to and from control unit 85. Capacity control tube 98 has a cathode 101, a plate 100 and is connected with a cathode bias resistor 102 by-passed by condenser 103, plate load resistor 104 which may be varied by means of tap switch 107, a source of plate voltage +B, not shown, by-passed by condenser 105 and a heater for cathode 101 also not shown. In order to control the grid to ground capacity of tube 98 in accordance with the present invention, the variable oscillator tuning condenser 95 and its series padding condenser 94 are connected in series between plate 100 and grid 99, and grid 99 is coupled to the variable frequency oscillator inductance 87 by means of blocking condenser 93. As long as the bias supplied from control generator 85 is zero, the circuit operates in the usual manner in which condenser 92 is varied in tuning the receiver causing oscillator 86 to cover a desired frequency range. Capacities 94 and 95 are made slightly smaller than they would be without the capacity tube 98 since their capacity is multiplied by a small factor by the tube gain. When a station is tuned in, if the resulting mean intermediate frequency is higher than the desired intermediate frequency, assuming the oscillator frequency of 86 is greater than the received signal frequency, control generator 85 will generate a positive bias increasing the gain of tube 98 and the capacity produced by this tube and hence reducing the oscillator frequency until the mean intermediate frequency is corrected. If the mean intermediate frequency is too low, the generated bias is negative reducing the capacity supplied by tube 98 and raising the oscillator frequency until the mean intermediate frequency is corrected. It is important in an automatic tuning system of this type that the correction of the oscillator frequency be limited as otherwise the system would tune into undesired channels. If the correction in the usual capacity control system is made correct at one of the frequency range, it will be too small or too

great at the other end. This present system will give substantially constant correction at any position of condenser 92 and hence equal corrections at both ends of any frequency band. Condensers 94 and 96 supply in conjunction with the various stray capacities of the system the desired shunt capacities to cause the system to produce equal increases and decreases in capacity for the same control bias changes regardless of the setting of condenser 92. If the stray capacities are of the correct value, either or both of condensers 94 and 96 may be omitted. In order to adjust the correction effect of tube 98 as bands are switched in an all wave receiver switch 107 is provided to change the load resistor 104 in accordance with the wave change switch. In general, resistor 104 will be decreased as the frequency of the oscillator 86 is increased. Switch 107 may be ganged with wave change switches 15 changing carrier circuit inductances and oscillator inductance 87. Oscillator tuning condenser 92 may be ganged with carrier circuit tuning condensers in the usual manner. Padding condenser 94 is for the purpose of decreasing the 20 oscillator frequency range and causing it to track at a fixed frequency difference with the carrier tuned circuits in the usual manner.

While a preferred form of my present invention has been shown and two applications, it is 30 not intended to limit the modifications which may be made except as set forth in the appended claim.

What I claim is:

A variable frequency oscillator system comprising a first thermionic tube having a cathode grid, and plate, a plurality of three-terminal coils, means to connect one terminal of each coil together, said connecting means being grounded, a parallelly-connected condenser and resistor 35 connected between said grid and said connecting means, a first switch for selectively connecting a second terminal of each of said plurality of coils to said plate, a second switch for selectively connecting a third terminal of each of said plurality of coils to said cathode, a condenser connected 40 between said first switch and said second switch, a variable output circuit comprising a serially connected resistor and condenser connected between said second switch and said connecting means, a second thermionic tube having a cathode, grid, screen grid and plate, said second thermionic tube serving as a reactance tube, a multi-tapped resistor connected between the anode circuits of said first and said second thermionic tubes, a third switch for selectively regulating the value of resistance of said multi-tapped resistor, a single means for simultaneously actuating said first, said second, and said third switches, apparatus to be tested, variable means 45 to supply energy from said output circuit to said apparatus to be tested, a cathode ray tube having horizontal and vertical deflection means, means to supply energy from said apparatus to said vertical deflection means, a supply source of alternating current, and a rectifier connected between said supply source and said first and said second thermionic tubes, said supply source also supplying alternating current potentials to both the control grid of said second thermionic tube and 50 said horizontal deflection means.
